(57) **CLAIM**

The ornamental design for a “media metering device,” as shown and described.

DESCRIPTION

FIG. 1 is a front right perspective view of a media metering device.

FIG. 2 is a front view of the media metering device of FIG. 1.

FIG. 3 is a rear view of the media metering device of FIG. 1.

FIG. 4 is a right side view of the media metering device of FIG. 1.

FIG. 5 is a left side view of the media metering device of FIG. 1; and,

FIG. 6 is a top view of the media metering device of FIG. 1.

The broken lines show portions of the media metering device that form no part of the claimed design.

1 Claim, 3 Drawing Sheets
